UNITED STATES PATENT OFFICE.

WILLIAM MACGOWAN, OF CHICAGO, ILLINOIS.

PRINTING-PRESS ROLL.

1,104,432.

Specification of Letters Patent.

Patented July 21, 1914.

Application filed April 10, 1914. Serial No. 830,894.

To all whom it may concern:

Be it known that I, WILLIAM MACGOWAN, a citizen of the United States, residing at Chicago, in the county of Cook and State of Illinois, have invented a new and useful Improvement in Printing-Press Rolls, of which the following is a specification.

My invention relates to certain new and useful improvements in printing-press rolls and is fully described and explained in the specification and shown in the accompanying drawings, in which:

Figure 1 is a longitudinal section through my improved device; Fig. 2 is an elevation of the same; Fig. 3 is a section on line 3 of Fig. 2; Fig. 4 is a perspective view of one of the clamping-brackets, and Fig. 5 is a perspective view of one of the sliding-blocks and bolt.

Referring to the drawings, 6 is a cylindrical roll in the periphery of which are milled slots 7, each of which is narrowed in its outer margin so that each slot is in T-shaped cross-section with its head inward.

The slots are preferably milled in a spiral direction, as shown. Outside of the roll are placed a number of rings 8. These rings are used in sufficient numbers to build up an enlarged surface on the roll as large or slightly larger than the electrotype which it is desired to use for printing. By varying the number of the rings, the size of the enlarged section can be varied at will. The rings are preferably provided with dowels 9 and with holes to register therewith so that the composite enlarged section possesses the desired solidity.

10 is the electrotype-plate which overlies the rings, as shown. The electrotype-plate is held in position upon the rings by clamps, such as that shown in Fig. 4, each of which has a downwardly-projecting end 11 engaging the roll, a horizontal web 12, a vertical web 13, and an overhanging lip 14 which engages the electrotype-plate. In the milled slots are blocks 15, each of which has an enlarged lower part and an upwardly-projecting reduced part, and these blocks are secured by bolts 16 to the clamps.

50. The description of the structure will of course make plain the mode of operation. The structure is advantageous in that the

roll has the enlarged section upon which the electrotype-plate rests, thereby providing a comparatively large space wherein the clamp 55 may lie without interfering with the paper being printed upon. Owing to this large space, the clamp can be made heavy, and it may be secured in place by a heavy bolt, whereas in prior structures of which I am 60 aware the electrotype-plate has been placed very close to the main surface of the roll so that the clamp which was to engage therewith and the bolt or screw which held the clamp in place had to be so small in size, in 65 order to clear the surface printed upon, as to make it necessarily weak in structure.

I realize that considerable variation is possible in the details of the construction herein shown, and I do not intend to limit 70 myself thereto, except as pointed out in the following claims, in which it is my intention to claim all the novelty inherent in the device as broadly as is permitted by the state of the art.

I claim as new and desire to secure by Letters Patent:

1. A printing-roll having an enlarged part to receive an electrotype, and reduced parts at the ends thereof, slots with overhanging 80 margins in the reduced parts of the roll, blocks therin, clamps overlying the reduced parts of the roll and overhanging the enlarged part to engage an electrotype thereon, and bolts engaging the clamps with the 85 blocks in the slots.

2. A printing-roll having, in combination, a series of rings forming an enlarged part of adjustable size to receive and support an electrotype, and a reduced part on which 90 said ring is fitted, the reduced part being provided with slots having overhanging margins, blocks in the slots, clamps whose tips overhang the enlarged part of the roll to engage an electrotype thereon, and bolts 95 connecting the clamps and blocks, for the purpose set forth.

In testimony whereof, I have hereunto set my hand this 7th day of April, 1914.

WILLIAM MACGOWAN.
